UNITED STATES PATENT OFFICE

ALICE ANTHONY, OF STERLING, ILLINOIS

DARNING SUPPORT

Application filed March 30, 1927. Serial No. 179,441.

5 My invention relates to a darning form or frame which is designed to facilitate the repair of hosiery, and the object thereof is to provide a frame embodying novel features of construction which will be apparent from the description hereinafter contained, and which render the device superior in certain respects to any devices for the same purpose known to me. In the appended claims I
10 have more particularly pointed out the essential elements of my invention, and distinguished it from the prior art, so far as I have knowledge of the same.

15 In the drawings Figure 1 is a face view of my invention in a preferred form;

Fig. 2 is a cross-section of the same in a plane indicated by the dotted line 2--2 of Fig. 1;

20 Figs. 3 and 4 are similar cross-sections of slightly modified forms of my invention;

Like reference characters indicate like parts in all the views of the drawings. Describing first the preferred form of my invention illustrated in Figs. 1 and 2, the 25 darning frame there shown consists of an elongated oval ring portion or rim member 1 which may conveniently be formed of wood, though celluloid, rubber, or hard compositions of other suitable material may be employed if desired, and a partition or

30 septum 2, of similar or other suitable material, which lies in a plane passing between the side faces of the ring member, in the present instance, though not necessarily, 35 centrally thereof, the parts being fastened together in any suitable manner as by glue, metal brads, or other means. The frame is of such size as to permit a sock or stocking of corresponding size to be smoothly received upon it without undue stretching, it being 40 contemplated in the use of my invention to provide frames of a variety of sizes appropriate for the repair of hosiery of various sizes.

45 In the form of my invention shown in Fig. 3, the partition member 3 is made removable, to which end it is constructed of a material sufficiently flexible to permit it to be sprung into the inside groove of the rim member 4.

50 The latter, as illustrated, is formed with a

narrow periphery, which has the effect of retaining a stocking in adjusted position upon the frame somewhat more effectively than a rim which is circular in cross-section.

In the form of my invention illustrated in Fig. 4 the rim is formed in two sections, 5 and 6, fixed to the partition 7, the parts being finished to present a peripheral surface similar to that of Fig. 3.

It will readily be understood that a stocking foot, or leg will be stretched by a darning frame of appropriate size so that it will lie in parallel sections on opposite sides of the rim portion, and that a darning needle may be effectively plied to weave a repair connecting the margins of a rent in the article. In any form of solid darning last the fabric of course lies flat upon the surface of the last and the needle must be worked up and down against the underlying impenetrable surface of the last, whereas in my improved darning frame the point of the needle may be carried down into the free working space beneath, and moreover a crotchet needle may be employed to repair what are known as "runners", which are longitudinal open lines in the fabric due to the breaking of a thread, this procedure being in many cases, particularly in the case of finely knitted fabrics, the best and most satisfactory method of making such a repair.

The central septum prevents the needle from being incautiously carried into the fabric on the side of the article opposite that being repaired, and prevents any flap extending inwardly from a rent on one side being caught by the needle when working upon a rent on the opposite side. The size and shape of my novel frame is such, moreover, that in use it will ordinarily lie flat, or nearly flat, in the palm of one hand of the person using it, and the partition serves to protect the hand against needle pricks due to incautious manipulation of the needle. Incidentally, this partition provides a suitable face for ornamentation, or the reception of advertising matter, in cases where my novel darning frames are distributed as premiums, or prizes, or as advertisements by those desiring to reach users of such devices.

While the cross-sectional dimensions of the rim of my frame may vary somewhat, it will be understood that they should be such as to provide adequate space between the opposite stretched sections of the article
5 (and on each side of the partition) for manipulation of the needle, a suitable proportionate size being shown in the drawings.

I claim:

10 A darning frame comprising a rim member in the form of an elongated oval ring of appropriate size to smoothly stretch a corresponding stocking into parallel sections on opposite sides of the ring, and a diaphragm of sheet material on the inside of
15 said ring forming a partition member lying in a plane passing between and spaced from the planes of said opposite sides whereby a working space is formed on each side of the partition.

20 In testimony whereof, I have subscribed my name.

ALICE ANTHONY.
